UNITED STATES PATENT OFFICE.

CHARLES A. SCOTT, OF ROME, NEW YORK, ASSIGNOR, BY MESNE ASSIGNMENTS, TO GENERAL CABLE CORPORATION, OF NEW YORK, N. Y., A CORPORATION OF NEW JERSEY.

WHEEL GUARD.

Application filed June 30, 1927. Serial No. 202,476.

This invention relates to wheel guards, and has as an object to provide a guard which is adapted to remove obstructions from a track upon which the wheels are travelling but which shall be flexible and yielding in order that if, due to inequalities in the track, the guard engages a substantial object, such as the track itself, or if the car or vehicle to which the guard is attached is derailed, no damage will result to the guard.

Other objects and advantages of the invention will appear hereinafter.

A preferred embodiment of the invention selected for purposes of illustration is shown in the accompanying drawings, in which,

Figure 1 is a side elevation of a mine locomotive showing the guard shoe attached.

Figure 2 is an enlarged side elevation of the guard.

Figure 3 is a front elevation of the guard.

For purposes of illustration, the guard has been shown as applied to an electric mine locomotive, and while the guard is adapted particularly for such use, it will be understood that the invention is not limited to such application. The conditions under which such locomotives operate are very rigorous, the tracks being usually laid unevenly, the grades being heavy, and the curves being sharp in many cases. Furthermore the tracks frequently become obstructed with loose earth, rock, etc. As a result of these conditions, derailments are frequent.

Such locomotives are frequently driven by electric current supplied by a cable which is wound up or paid out by a reel mounted thereon. It frequently happens that in going down grade the locomotive travels faster than the cable is wound by the reel, with the result that the locomotive overruns the cable and cuts or damages the same.

Accordingly, it is desirable to provide a guard which shall clear the track of loose obstructions and which shall also pick up or push ahead the cable when the reel fails to wind fast enough. Various expedients such as rigid guards have been tried but have been found unsatisfactory because when adjusted sufficiently closely to the track to accomplish the desired purpose, they have been broken off or damaged by contact with the track due to the inequalities therein. On the other hand, when raised sufficiently to clear such track inequalities, the rigid guards are ineffective for guarding purposes. In any

event, upon derailment of the locomotive such rigid guards are invariably damaged.

According to the present invention it is proposed to provide a guard of yielding, resilient construction which may be adjusted in close proximity to the track, but which may be displaced when brought into contact with the track or with a fixed object without damage. The guard should be sufficiently firm on the other hand to cause displacement of loose objects and to pick up the cable when occasion arises.

Referring to the drawing, in its preferred embodiment the guard comprises a body member 1, preferably substantially cylindrical in shape, with which is integrally formed a forwardly and downwardly protruding prong 2 having a substantially scoop-shaped front face 3 terminating in the lip 4. At either side the prong 2 is provided with the depending flanges 5 and 5'.

The guard is preferably formed of rubber or other suitable yielding resilient material, a composition comprising 60% pure rubber, 15% carbon black and 25% reclaimed rubber having been found to be a suitable composition for the purpose.

Preferably the body member 1 is also cored to provide a longitudinally extending passage 6 which may fit over and be clamped to a fixed cylindrical member 7 in order to secure the guard in proper position. In mine locomotives, the sand pipe extending from the sand box 8 has been found a convenient support for the guard and by clamping the guard to the pipe in the manner shown the passage 6 through the guard becomes an extension of the sand pipe and serves to distribute the sand in close proximity to the rail.

As illustrated to best advantage in Figures 2 and 3, the lip 4 extends transversely across the head of the rail 9 and the flanges 5 and 5' which are spaced apart a distance sufficient to clear the shoulders of the rail extend downwardly to a point preferably below the upper surface of the rail.

Due to the flexible resilient construction of the guard, it is permitted to flex to one side or the other or it may be bent backwardly without damage when fixed objects are encountered, but it may resume its original position after the inequality is passed or as soon as the locomotive is replaced upon the track. On the other hand, the guard is sufficiently rigid

and non-yielding to throw aside loose material such as earth and stones which are a frequent cause of derailing.

It is to be understood that the invention 5 may be variously modified and embodied within the scope of the subjoined claims.

I claim as my invention:

1. A wheel guard comprising a member of flexible resilient material having a longitudinally extending passage therethrough, said passage being adapted to receive a fixed support in frictional engagement, said member extending into close proximity with the surface upon which the wheel rests, and adapted 10 to yield upon encountering fixed objects.
2. A wheel guard comprising a member of flexible resilient material having a portion adapted to be secured to a fixed support, said member having a prong extending forwardly and downwardly into close proximity with the surface upon which the wheel rests, and adapted to yield upon encountering fixed objects. 15
3. A wheel guard comprising a member of flexible resilient material having a portion adapted to be secured to a fixed support, said 20

member extending into close proximity with the surface upon which the wheel rests, and adapted to yield upon encountering fixed objects, said member having spaced side flanges 30 extending below the said surface.

4. A wheel guard comprising a member of flexible resilient material having a portion adapted to be secured to a fixed support, said member having a prong extending forwardly 35 and downwardly into close proximity with the surface upon which the wheel rests, and adapted to yield upon encountering fixed objects, said prong being provided with spaced side flanges extending below the said surface. 40

5. A wheel guard comprising a member of flexible resilient material comprising a body portion having a longitudinally extending passage therethrough and a prong extending forwardly and downwardly therefrom into close proximity with the surface upon which the wheel rests. 45

In testimony whereof, I have signed my name to this specification this 21st day of June, 1927.

CHARLES A. SCOTT.
